United States Patent Office.

WILLIAM HACHENBERG, OF WHITE PIGEON, MICHIGAN.

Letters Patent No. 79,068, dated June 23, 1868.

IMPROVED WASHING-MACHINE.

The Schedule referred to in these Letters Patent and making part of the same.

TO ALL WHOM IT MAY CONCERN:

Be it known that I, WILLIAM HACHENBERG, of White Pigeon, in the county of St. Joseph, and State of Michigan, have invented a new and useful Improvement in a Washing-Machine; and I do hereby declare that the following is a full, clear, and exact description thereof, which will enable others skilled in the art to make and use the same, reference being had to the accompanying drawings, forming part of this specification.

Figure 1 is a top view of my machine.

Figure 2 is a vertical longitudinal section of the same, taken through the line $z z$, fig. 1.

Similar letters of reference indicate corresponding parts.

My invention has for its object to improve the construction of washing-machines, so as to make them more convenient and effective in operation; and it consists in the construction and combination of the various parts, as hereinafter more fully described.

A is the box or tub of the machine, the side walls a^1 of which are vertical, and the end walls a^2 of which incline inward, so that the said box may be shorter at its bottom than at its top, as shown in fig. 2.

B are timbers, the bottoms of which are so formed as to fit into the angles or corners formed by the intersection of the bottom, a^3 , and inclined end walls a^2 , with the vertical side walls a^1 of the box A. The upper sides of the timbers B are curved or hollowed out into the form of a semicircle, as shown in fig. 1.

Along the curved sides of the timbers B are pivoted the journals of the rollers C; in the arc of a circle, and in such a way that a narrow space may be left between the said rollers for the free passage of the water.

D are inclined aprons, extending from the upper rollers C to the ends of the box A, as shown in fig. 2, for convenience in putting in and taking out the clothes, and to guard against said clothes dropping down between the rollers C and the end boards or walls a^2 of the box A.

E is the rubber, which is made in the shape of a half cylinder, and which is formed by attaching cleats or bars c^1 to the curved edges of the semicircular end blocks e^2 .

The cleats e^1 I prefer to make in about the shape shown in fig. 2, as taking a better hold upon the clothes. e^3 is the shaft of the rubber, which is securely attached to the semicircular end blocks e^2 , and to the ends of which are attached the journals or pivoting-pins e^4 , upon which the said rubber works.

The journals e^4 enter and work in vertical grooves formed in the inner sides of the side walls a^1 , as shown in fig. 1.

The journals e^4 and shaft e^3 are placed below the centres of the circles, of which the end blocks e^2 are segments, so that when the said rubber is rocked its sides may bear harder upon the clothes than its lower or middle part.

To the centre of the shaft e^3 is rigidly attached a vertical arm, F, the upper part of which is slotted to receive the end of the connecting-rod G, which is pivoted to it by a pin passing through it, and through one or the other of the holes formed through the slotted part of the arm F, so that the throw of the rubber E may be regulated, as desired.

The outer end of the connecting-rod G is pivoted to the lever H, the lower end of which is pivoted to the outer end of the arm I, attached to and projecting from the end of the box or tub A.

By this construction the rubber E is operated to rub the clothes, by moving the upper end of the lever H back and forth.

If desired, the outer end of the connecting-rod G may be pivoted to the crank of a crank-shaft, to one end of which a hand-crank is attached, and to the other end of which is attached a balance-wheel.

J is a shaft, which is pivoted to the side walls a^1 of the box A, near one end of said box, and to which are attached two parallel arms or bars K, which pass down between the ends of the rubber E and the side walls of the box A, resting upon the journals or pivoting-pins e^4 of said rubber E.

To one of the projecting ends of the shaft J is attached one end of a spring-lever, L, so that by bearing down upon the said spring-lever L the bars K may be pressed down upon the journals e^4 , pressing the rubber E down upon the clothes with any desired force.

M is a toothed rack, attached to the side of the box A, the teeth of which take hold of the spring-lever L, holding it securely in place, when adjusted to give the desired pressure.

I claim as new, and desire to secure by Letters Patent—

The combination of the curved sides B, bearing the rollers C, segmental rubber E, whose journals e⁴ are hung in vertical slots, slotted bar F, connecting-bar G, lever-handle H, shelf I, shaft J, bars K, and spring-lever L, all arranged as described for the purpose specified.

WILLIAM HACHENBERG.
